RECEPTACLE

Herbert L. Reitzes, Philadelphia, Pa.

Application October 10, 1946, Serial No. 702,477

7 Claims. (Cl. 229—85)

1

This invention relates to receptacles, such as bags or envelopes, preferably made of transparent sheet material, and more particularly to improved closures for the same which while providing adequate sealing of the receptacles permit of easy opening for access to the contents.

It has heretofore been proposed to make bags or envelopes of synthetic cellulosic sheet material known as cellophane or the like, and of hydrochlorinated rubber film known as Pliofilm. It has also been proposed to provide top and bottom closures for such bags or envelopes by heat sealing the top and bottom portions thereof.

The contents of such bags or envelopes may consist of candy, nuts, or other edible materials, or other small articles, which it is desired to package in sealed, air-tight condition and protected from water and moisture.

With the receptacles heretofore available, when it is desired to obtain access to the contents, it is necessary to break or tear the package, but this is difficult by reason of the lamination of the material at the heat sealed portion, giving the same added strength, and also because of the initial resistance to tearing of the sheet materials commonly employed.

It is the principal object of the present invention to provide, in a bag or envelope, an improved closure which embodies structure to permit of ready access as desired to the contents of the bag or envelope.

It is a further object of the present invention to provide, in a bag or envelope of the character aforesaid, an improved closure which will be air- and moisture-tight, but which will permit of ready access to the contents as desired.

It is a further object of the present invention to provide an improved closure for bags or envelopes of the character aforesaid which embodies a built in tab portion, which is severable from the adjoining portions of the closure, for permitting access to the contents.

Other objects and advantageous features of the invention will be apparent from the specification and claims.

The nature and characteristic features of the invention will be more readily understood from the following description, taken in connection with the accompanying drawings forming part hereof, in which:

Figure 1 is a front elevational view of a bag or envelope in accordance with the present invention;

Fig. 2 is a fragmentary sectional view, en-

2

larged, taken approximately on the line 2—2 of Fig. 1;

Fig. 3 is a fragmentary sectional view, enlarged, taken approximately on the line 3—3 of Fig. 1;

Fig. 4 is a front elevational view of another embodiment of the invention;

Fig. 5 is a front elevational view of another embodiment of the invention; and

Fig. 6 is a front elevational view of another form of the invention.

It should, of course, be understood that the description and drawings herein are illustrative merely, and that various modifications and changes may be made in the structure disclosed without departing from the spirit of the invention.

Referring more particularly to the drawings, the bag or envelope 10 is preferably formed from a strip or sheet of thin tough transparent material to permit of observation and inspection of the contents. The bag or envelope 10 may be made of any desired sheet material, such as synthetic cellulosic sheet material, lacquer-coated, if desired, and sold under the name of cellophane, or may comprise hydrochlorinated rubber film or sheet material, sold under the name of Pliofilm.

The sheet material is formed in any desired manner into a flat hollow tube and may have a longitudinally extending seam 11, heat sealed or otherwise secured. The bag or envelope is preferably permanently closed at one end 12, such as the bottom, and this closure may be formed in any desired manner.

In the form of the invention illustrated in Figs. 1 to 5, inclusive, the open or top end of the bag or envelope has a folded strip or label 13 applied transversely with respect to and covering the upper extremities of the bag or envelope 10. The upper edge portions of the bag or envelope 10 are suitably united at their interiors, and the strip or label 13 secured to the exterior of the upper edges in any desired manner, but preferably by heat sealing, to provide a sealed area 14 extending, from the upper marginal edges 15 of the bag 10, downwardly to a terminus 16 spaced above the lower edges 17 of the strip 13. In the sealing, a part of the upper edge portions is preferably left unsealed, as at 18. The marginal edge 19 of the unsealed portion may be V-shaped, as illustrated at 19a in Fig. 1, may be curved, as illustrated at 19b in Fig. 4, or may consist of a diagonal line, as indicated at 19c in Fig. 5. The unsealed portion 18 is, however, ter-

minated below the upper terminal edges 15 of the bag or envelope so that a seal is provided across the top edge of the bag or envelope 10.

Along and spaced upwardly a short distance from the marginal edges 19a, 19b and 19c, a plurality of perforations 20 are provided which are preferably applied in such a manner as to further join and seal the material at the area surrounding each of the perforations 20, thereby obviating any tendency to leakage at the perforations. The perforations 20 are terminated a predetermined distance below the upper marginal edges 15 to permit of the complete sealing across the top edge of the bag or envelope 10, thereby obviating any tendency to leakage of air or water. There is thus provided a laminated severable tab 21 in the top closure.

In the form of the invention illustrated in Fig. 6, the strip or label 13 may be omitted. The sealing is applied only to the sheet material of which the bag or envelope 10 is made, with a lower terminus 16, with an unsealed portion 18 and a margin 19 bounding the unsealed portion 18. Perforations 20 are provided as before to bound a tab 21a.

When it is desired to obtain access to the contents of the receptacle, the tab portion 21 or 21a is grasped between the thumb and first finger, and the same may be readily severed from the remaining portion of the bag or envelope 10. The strip or label 13 if employed is simultaneously severed. The contents may then be pressed against the marginal edges 19 to rupture the seal at that location, or, if desired, the marginal edges 19 may be separated with the fingers.

It will thus be seen that there is provided a package or receptacle which will remain in air-tight and liquid-tight condition, but which may be readily opened for the removal of the contents as desired.

I claim:

1. In a closure for the flattened tubular end of a package, a sealed portion extending transversely across the end and having an inner boundary with part thereof spaced inwardly from the transverse terminus and another part there-

of spaced inwardly at a lesser distance from the terminus, said other part of said boundary having a weakened portion therealong between said boundary and said terminus, said weakened portion and the terminus defining a severable tab of a width corresponding to the transverse length of the other boundary part and extending inwardly from said terminus, said weakened portion and said other part of said boundary defining a sealed band of reduced width accessible and readily breakable after severing of said tab for access to the interior.

2. A closure as defined in claim 1, in which the weakened portion comprises perforations.

3. A closure as defined in claim 1, in which said other portion of said boundary is of V-shape.

4. A closure as defined in claim 1, in which said other portion of said boundary is of curved shape.

5. A closure as defined in claim 1, in which said other portion of said boundary includes a part extending diagonally with respect to the terminus.

6. A closure as defined in claim 1, in which a transverse strip encloses and covers said end and the strip is provided with a weakened portion aligned with said other weakened portions.

7. A closure as defined in claim 1, in which the weakened portion comprises perforations, and a transverse strip encloses and covers said end and the strip is provided with perforations aligned with said other perforations.

HERBERT L. REITZES.
